UNITED STATES PATENT OFFICE

GARFIELD J. UNDERWOOD, OF AMSTERDAM, NEW YORK, ASSIGNOR TO MOHAWK CARPET MILLS, INC., OF AMSTERDAM, NEW YORK, A CORPORATION OF NEW YORK

FRINGE

Application filed June 7, 1932. Serial No. 615,782.

This invention relates to fringes of the type used, for example, with pile fabrics in the manufacture of rugs, and is concerned more particularly with a novel fringe which is superior to those heretofore employed in that the fringe has a fuller, richer body and the fringe ends cannot be readily pulled out. The invention also comprehends a method of producing the new fringe rapidly and at low cost.

10 Fringe for use with pile fabrics has heretofore commonly consisted of warp threads and weft threads interlaced therewith to form a fabric, the warp threads being arranged in groups across the fabric with spaces between 15 the groups so that the fabric consists of several webs which are to form the bodies of pieces of fringe while the spaces between the webs are filled only with weft threads which form the fringe ends. In weaving such a 20 fabric, the groups of warp threads are manipulated by the usual heddle mechanism to form sheds in which the weft threads are inserted by a shuttle or needle and the fabric thus produced has a selvedge at both sides thereof. The fabric may include several webs between the two selvedges and to form the bands of fringe, the weft threads are cut at appropriate intervals. Each band of fringe 25 includes web and weft threads which form the fringe ends but only two of the bands into which the fabric is divided have selvedges which will prevent the weft threads from being pulled out. In the remainder of the bands, the weft threads are not bound to the warp 30 threads but are simply interlaced therewith and when one of the intermediate bands is attached to a piece of fabric in the usual way by stitching, the loose fringe ends are not securely held in position and are easily detached.

35 The present invention is directed to the provision of a fringe which may be woven in the form of a fabric made up of a plurality of webs or bands, the fabric being so constructed that when it is sub-divided into the individual

fringe bands, the latter may be attached to the pile fabric in such a way as to have a selvedge which prevents the weft threads from being readily pulled loose.

The new fabric is woven in the usual way 50 and it comprises groups of warp threads arranged in pairs and weft threads which are interlaced with all of the warp threads. The warp threads used as binders are of small size and preferably of cotton and the weft threads 55 which form the loose ends of the fringe are of much larger size and of the type known as cords, these fringe cords also preferably being made of cotton. The binder threads and fringe cords are interwoven in such manner 60 that each cord passes straight through each of the webs formed by the interweaving of the fringe cords and binder threads and passes alternately over and under each binder thread in a web, each fringe cord thus extending straight across the entire fringe fabric and lying parallel to the adjacent cords. The pairs of groups of warp threads are spaced a substantial distance apart with the 65 spaces filled only by weft threads, and the groups of a single pair are spaced apart a short distance by the omission of a relatively few warp threads. Upon completion of the fabric, it is sub-divided into fringe pieces by cutting the weft threads midway between the 70 pairs of groups of warp threads, and each piece of the fabric thus produced comprises a pair of groups of warp threads spaced a short distance and weft threads interlaced with the warp threads and extending out to either 75 side of the two groups of warp threads. Each piece is then folded lengthwise along a line which lies between the two groups of warp threads, only the weft threads being bent in this folding operation, and the two webs of 80 the piece are thus placed face to face, ready to be laid on the fabric to which the fringe is to be attached by stitching.

85 With this arrangement, it will be observed that each fringe end consists of a length 90

of weft which is doubled upon itself and the piece of fringe has a selvedge or margin along which the weft threads are bent back upon themselves. Since there are no warp threads in the space in which the folding occurs, there is no bulging by reason of the folding and the two webs of each piece of fringe may lie in close contact and do not give the finished article an undesirable thickness along the surface where the fringe is attached. At the same time, the fringe ends are securely held in place and cannot be readily pulled loose and the fringe has double the usual number of ends.

15 For a better understanding of the invention, reference may be had to the accompanying drawing, in which

Fig. 1 is a plan view of a piece of the new fabric illustrating the manner in which it is woven;

Fig. 2 is a view of a piece of the fringe in end elevation;

Fig. 3 is a lengthwise view through a piece of pile fabric to which the fringe is attached; and

Fig. 4 is a plan view of the fabric and fringe illustrated in Fig. 3.

Referring now to the drawing, the manner of weaving the new fringe is illustrated in Fig. 1 and the fabric which is sub-divided to form the pieces of fringe is there illustrated as comprising groups 10 of warp threads arranged in pairs with the groups of a single pair separated by a relatively small space representing the omission of a few warp threads. The distance between adjacent pairs of groups of warp threads is relatively much greater and represents the omission of a much larger number of warp threads, the width of the space being dependent on the length of the fringe ends desired. In weaving the fabric, the warp threads pass through the eyes of the heddles and are manipulated in the usual way to form sheds through which weft threads 11 are inserted. Those portions of the weft threads which extend across the large spaces between pairs of groups of warp threads constitute the fringe ends while the interlaced warp and weft threads form the body of a piece of fringe, the body consisting of the two webs 10a and 10b.

When the fringe fabric is completed, it is sub-divided into pieces of fringe by cutting the weft threads along lines 12 and each piece thus made is then folded along a line 13 lying between the two groups of warp threads present in the piece. The two webs 10a and 10b then lie one against the other as illustrated in Fig. 2 and the exposed portions 14 of the weft threads between the two groups constitute a selvedge.

In attaching the fringe to a pile fabric such as that illustrated at 15 in Fig. 3, the fringe folded as shown in Fig. 2 is laid upon the

heading 16 at the end of the fabric, from which the pile tufts have been omitted, and the piece of fringe is secured in place by one or more lines of stitching 17 which pass through the two webs and bind the webs to the heading and also secure the fringe ends 18 in place.

The completed fringe has more body and fullness than the ordinary fringe because it has twice as many ends as a fringe produced in the ordinary manner. Also, each fringe end is doubled upon itself and bound securely in place by the stitching and an end can be pulled out of the fringe only with great difficulty. By forming the fringe in the manner described with the warp threads arranged in pairs of groups separated by spaces in which there are no warp threads, the folding of the fringe to provide the selvedge can be accomplished without undesirable wrinkling or bulging, and the two webs 10a and 10b of each piece of fringe lie in flat face contact and can be secured to the pile fabric without difficulty.

The new fringe is superior to the fringes made in the ordinary manner in that each fringe has a selvedge, that is, each fringe end passes around the edge of the piece so that an end cannot be easily pulled out, whereas in fringes produced by prior methods, only the two edge portions of the fabric have the fringe ends bound in this manner and in all the intermediate bands of fringe, the ends are held in place loosely. Also, the new fringe is superior to the ordinary fringe in that it has twice the number of fringe ends and, therefore, has a greater body and fullness and a much more pleasing appearance.

I claim:

1. The combination with a pile fabric having a heading of a fringe attached to said heading, said fringe comprising a row of relatively large fringe cords interwoven as weft with spaced groups of binder threads of relatively small size as warp to form webs connected by exposed portions of said fringe cords, said webs being substantially wider than the space between them and the fringe cords exposed between said webs being bent to bring one web into face contact with the other, each fringe cord having free ends substantially longer than the width of said webs and passing directly through each web and across the space between said webs, and means for attaching said fringe to the upper surface of said heading, said means passing through both webs and said heading.

2. A fringe for use with a floor covering which comprises a row of straight relatively large fringe cords lying side by side and two groups of binder threads of relatively small size interwoven therewith to form a pair of webs lying side by side in spaced relation and connected by portions of said fringe cords extending across said space, each cord passing

straight across one web, the space between said webs, and the other web, and passing alternately over and under the binder threads in said webs, said webs being of substantially 5 greater width than the space between said webs, and the fringe cords in said space being bent to bring said webs into face contact and in registry, said bent cords forming a selvage and the free ends of said cords being 10 substantially longer than the width of said webs.

In testimony whereof I affix my signature.
